FOLDING TOP FOR RUMBLE SEATS

Tracy Selden Newton, Jr., Atlanta, Ga.

Application April 28, 1930, Serial No. 448,143

13 Claims. (Cl. 296—99)

My present application is a continuation in part of my application filed January 3, 1928, Serial No. 244,131, and like such application, is directed to an invention in folding tops for rumble seats.

5 One of the objects of my invention is the provision of a top which may be applied to automobiles in use, or at the time of manufacture, and which can be quickly opened or raised to position for use, and which can be instantly folded out of 10 use and contained snugly in the back of the automobile.

Another object of my invention is the provision of a folding or collapsible top which can be easily stored or placed in position for use, and which 15 will, when in use, make a perfect top and conform to the general outline of the automobile, in order that an attractive and ornamental appearance will be assured.

Another object of my invention is the provision 20 of a folding top which can be easily adjusted to the desired position, and which can be produced at such a small cost as to make its use highly desirable.

Another object of my invention is the provision 25 of a folding top which will possess merit and advantages in point of simplicity and durability, ease of operation, and which in all particulars will prove efficient, desirable and practicable.

A further object is to provide a folding top for 30 rumble seats which in collapsed condition may be stored between the seat and back of the rumble, and which from such stored position may be raised, and either extended to form a top for the rumble seat, or swung bodily to a position behind 35 the seat back, for entirely clearing the rumble seat, to thereby allow of ready ingress and egress therefrom, and to allow passengers to use the rumble seat without a top is so desired.

A further object is to provide in connection 40 with such top a side curtain construction which will effectively enclose the rumble seat space and protect the occupants thereof from the elements.

Another object of my invention is to provide 45 means for detachably connecting the top structure, when in extended position, to the original top of the vehicle in such manner as to render the joint between the permanent and folding top weather proof.

Another object is to provide a side curtain construction which may be quickly attached to and 50 detached from the folding top structure, and which utilizes the rain gutter around the deck opening in providing a weather proof enclosure for the rumble seat.

55 A further object of the invention is to provide

a rumble seat top having details of construction directed to economy in manufacture, and efficiency and reliability in operation.

With these and other objects in view which will 60 become apparent as the description proceeds, the invention resides in the construction, combination and arrangement of parts hereinafter more fully described and claimed.

In the drawings, which show one of the forms 65 which the invention may take, with certain modifications,—

Figure 1 represents a perspective view of an 70 automobile of the coupé type having a rumble seat with my folding top applied, and shown in position for use.

Figure 2 represents a side elevation on a larger 75 scale of the frame work of my folding top, showing parts of the seat and the permanent top.

Figure 3 represents a top plan view, on a smaller 80 scale than Figure 2, with the central parts broken away, for compactness of illustration, of the top in extended position, the cover being removed.

Figure 4 represents a side elevational view, on an enlarged scale, of a portion of the top frame 85 work, showing the gear connection between the front or inner parallel bars forming a portion of the forward frame section, and the upper branches of the braces.

Figure 5 represents a top plan view of Figure 4.

Figure 6 represents a fragmentary view in side 90 elevation showing the form that the top rear cross member may take when formed of metal, instead of the wooden form shown in Figure 2.

Figure 7 represents a side view of the frame 95 shown in folded or collapsed position and out of use down between the rumble seat and its back.

Figure 8 represents a side view of the frame when it has been raised out of the stored position of Figure 7, after the rumble seat has been raised, and swung bodily upward about the links 95 in position to either be extended to top supporting position of Figure 2, or to be swung to the position behind the seat back illustrated in Figure 10.

Figure 9 represents a vertical sectional view, on an enlarged scale, on the line 9—9 of Figure 3, 100 showing the connection between the collapsible top and the original car top.

Figure 10 represents a side view of the frame 105 shown in folded or collapsed condition, and disposed in rear of the hinged back of the seat.

Figure 11 represents a fragmentary top plan view of the rear portion of the original car top and the front portion of the frame, in detached condition, showing the difference in curvature 110

between these parts. In this form both the original top is curved, and the front cross member or bar of the top, the curvature of the latter being on a greater radius than the curvature of 5 the top.

Figure 12 represents a view similar to Figure 11, in which the back of the original top is straight. In this instance, the front cross member or bar of my folding top is curved in the reverse direction to that shown in Figure 11. 10

Figure 13 represents a view similar to Figure 4, showing a modified form of means for holding the forward frame section in braced position when the top is extended.

15 Figure 14 represents a top plan view of the parts shown in Figure 13.

Figure 15 represents a fragmentary vertical sectional view showing a connection of the top to the rumble seat back particularly adaptable to Ford cars. 20

Figure 16 represents a side elevational view of my top, extended in position with the top material and the side curtains on.

25 Figure 17 represents a fragmentary cross section on the line 17—18, 17—18 of Figure 16, showing the manner of fastening the top material and side curtains, such view looking forwardly.

Figure 18 is a fragmentary vertical sectional view along the line 17—18, 17—18 of Figure 16, 30 looking to the rear.

Figure 19 represents a perspective view of the top in extended position with the top material and side curtains on.

In referring to the drawings, it will be understood that my folding top is particularly designed 35 for use in connection with the coupé or roadster type of automobile 1, which is equipped with the rumble seat structure composed of the seat 2 (Figure 7), and the hinged back 3, although the 40 top may be used in any situation where it would perform its functions in an efficient manner.

The top is of simple construction, and includes the pair of front or inner parallel bars 4 which, when the top is open, are in a horizontal position 45 and lie close to the usual or original top 5 of the automobile. The bars 4 have their inner ends pivoted in the outer ends of the boxes 7 of the rectangular frame 8, said bars 4 carrying gear wheels 9 which mesh with racks 10. These racks 50 are carried on the upper ends 11 of the upper branches 12 of the brace members, the lower branches of which are indicated at 14. The branches 12 and 14 are pivotally connected together at 13, and brace the frame when in extended position. 55

The front bars 4 may be connected at their forward ends by a cross member or cross bar 6 to form a forward frame section. This section is hinged to the rear frame section 8, which includes the pair of side bars and the central cross bar 8' of the frame as a whole. The side bars of the rear frame section 8 at their rear ends are pivoted as at 15, to the upper ends of the pair of back bars 16, the lower ends 17 of which 60 are pivoted to the lower ends of the braces and to the upper ends of the curved links 18. Such links at their lower ends are pivoted at 19 to the fastenings or supports 20, which are fastened to the hinged back 3 of the rumble seat below the upper edge thereof, and form the anchorage 65 for the top. The back bars with their cross bar 16' form a back frame section to which the rear frame section is pivoted. 70

75 From this construction it will be noted that I provide the forward frame section, including the

pair of front supporting bars, the open frame forming the rear top support and the pair of two-part braces, and that the folding of these braces rearward causes the racks 10 thereon to turn the pinions or gear wheels 9 of the bars 4 to fold said bars back upon the frame 8, and also causes the rear frame 8, together with the forward frame folded thereon, to fold down against the back bars 16. This operation brings the parts into the position shown in Figure 8, in which the frame members and back bars are collapsed in overlapping position so as to occupy a minimum of space. The moving inward or forward of the braces from this position, causes the frame to open and assume the position shown in Figures 80

85 members and back bars are collapsed in overlapping position so as to occupy a minimum of space. The moving inward or forward of the braces from this position, causes the frame to open and assume the position shown in Figures 85

90 members and back bars are collapsed in overlapping position so as to occupy a minimum of space. The moving inward or forward of the braces from this position, causes the frame to open and assume the position shown in Figures 90

95 members and back bars are collapsed in overlapping position so as to occupy a minimum of space. The moving inward or forward of the braces from this position, causes the frame to open and assume the position shown in Figures 95

100 members and back bars are collapsed in overlapping position so as to occupy a minimum of space. The moving inward or forward of the braces from this position, causes the frame to open and assume the position shown in Figures 100

105 members and back bars are collapsed in overlapping position so as to occupy a minimum of space. The moving inward or forward of the braces from this position, causes the frame to open and assume the position shown in Figures 105

110 members and back bars are collapsed in overlapping position so as to occupy a minimum of space. The moving inward or forward of the braces from this position, causes the frame to open and assume the position shown in Figures 110

115 members and back bars are collapsed in overlapping position so as to occupy a minimum of space. The moving inward or forward of the braces from this position, causes the frame to open and assume the position shown in Figures 115

120 members and back bars are collapsed in overlapping position so as to occupy a minimum of space. The moving inward or forward of the braces from this position, causes the frame to open and assume the position shown in Figures 120

125 members and back bars are collapsed in overlapping position so as to occupy a minimum of space. The moving inward or forward of the braces from this position, causes the frame to open and assume the position shown in Figures 125

130 members and back bars are collapsed in overlapping position so as to occupy a minimum of space. The moving inward or forward of the braces from this position, causes the frame to open and assume the position shown in Figures 130

135 members and back bars are collapsed in overlapping position so as to occupy a minimum of space. The moving inward or forward of the braces from this position, causes the frame to open and assume the position shown in Figures 135

140 members and back bars are collapsed in overlapping position so as to occupy a minimum of space. The moving inward or forward of the braces from this position, causes the frame to open and assume the position shown in Figures 140

145 members and back bars are collapsed in overlapping position so as to occupy a minimum of space. The moving inward or forward of the braces from this position, causes the frame to open and assume the position shown in Figures 145

150 members and back bars are collapsed in overlapping position so as to occupy a minimum of space. The moving inward or forward of the braces from this position, causes the frame to open and assume the position shown in Figures 150

155 members and back bars are collapsed in overlapping position so as to occupy a minimum of space. The moving inward or forward of the braces from this position, causes the frame to open and assume the position shown in Figures 155

160 members and back bars are collapsed in overlapping position so as to occupy a minimum of space. The moving inward or forward of the braces from this position, causes the frame to open and assume the position shown in Figures 160

165 members and back bars are collapsed in overlapping position so as to occupy a minimum of space. The moving inward or forward of the braces from this position, causes the frame to open and assume the position shown in Figures 165

170 members and back bars are collapsed in overlapping position so as to occupy a minimum of space. The moving inward or forward of the braces from this position, causes the frame to open and assume the position shown in Figures 170

175 members and back bars are collapsed in overlapping position so as to occupy a minimum of space. The moving inward or forward of the braces from this position, causes the frame to open and assume the position shown in Figures 175

180 members and back bars are collapsed in overlapping position so as to occupy a minimum of space. The moving inward or forward of the braces from this position, causes the frame to open and assume the position shown in Figures 180

185 members and back bars are collapsed in overlapping position so as to occupy a minimum of space. The moving inward or forward of the braces from this position, causes the frame to open and assume the position shown in Figures 185

190 members and back bars are collapsed in overlapping position so as to occupy a minimum of space. The moving inward or forward of the braces from this position, causes the frame to open and assume the position shown in Figures 190

back to assume its fully closed position. Figure 3 illustrates the width of the frame as compared to the rumble seat back and deck opening, 27 being the gutter around the opening which defines the 5 dimensions thereof.

From the foregoing it will be noted that the folding top supporting structure carrying the top as a whole, is pivoted to the pair of curved links 18 at their upper ends, while the lower 10 ends of said links are pivoted to the pair of securing brackets or supports 20 which are rigidly mounted on and movable with the hinged back, and this is a feature of paramount importance as it allows the frame with 15 the top material to be bodily raised upon the links to a position from which it may be extended upwardly and forwardly for use, or may be swung in collapsed position backwardly and downwardly and disposed in the rear of the 20 back seat where it is out of the way and where if desired it may be protected by a suitable covering, and a position from which it can be folded or collapsed and bodily lowered by the links to a storage position between the seat and back 25 when the latter is closed down, all of which insures a practical and useful device of this character.

The heels 18', at the upper end of the links 18, co-operating with similar heels at the lower 30 ends of the rear bars 16, maintain the top when in raised position, either collapsed, as in Figure 8, or extended as in Figure 2, against folding forwardly around the pivots which connect the braces, rear bars, and the links together. In 35 being lowered rearwardly and backwardly, to assume its position behind the seat back, the top supporting frame pivots in such relationship with the links that the heels spate, so as not to interfere with these movements. There are also 40 co-operating heels 18² between the lower ends of the links and the supports 20, which prevent the links from folding backwardly from the raised position, but permit them to pivot forwardly and downwardly to carry the frame to 45 storage position.

The supports 20 may pass through the seat back and caps 20' may be screwed on their projecting ends up against the seat back to hold them tightly in position. In Figure 15 I have 50 shown a construction particularly adaptable for Ford cars of the Model A type, and in this construction a shoe 35 is shaped to fit against the inwardly projecting flange 36 of the metal seat back at the top of the upholstery 37, such shoe 55 abutting against a shoulder 38 formed where the reduced shank 39 merges with the larger portion of the support 20, to thereby form an even bearing surface for the shoulder and co-operate with the flange and back metal section 60 of the seat back in rigidly maintaining the support. Where the seat back is of such construction that it forms a bearing surface for the shoulder 8, the shoe may be dispensed with.

The upper ends of the back bars 16 may be 65 bent slightly forwardly and provided with a rear cross bar 16' supporting a cross member of wood 16², for shaping the top material where it folds over the corner formed at this point. Or, if desired, the upper ends of the back bars 70 may be curved forwardly as indicated in Figure 6, and connected by a transversely curved metal cross member 16³ to shape the top. Brackets 38 may be used to connect the rear pivots of 75 the frame 8 with the upper ends of the back bars.

If desired, the upper ends of the brace members 12, and the racks 10, may be connected by a cross rod similar to the rod 33, shown in Figure 14, to insure the brace members pivoting in unison with reference to the frame 8, to 80 ease the break of the brace rearwardly on one side of the frame, when the brace on the opposite side thereof is broken. The braces on both sides will break when that on one side is broken, without the use of the rod, due to the transmission of motion through the forward frame, but the use of the rod will be advantageous in easing this operation, by transmitting the motion directly from one rack to the other, thus doing away with any drag should the forward frame 85 tend to twist, which drag would tend to interfere with the simultaneous operation of the gear ing.

I may, instead of using the rack and gear connection between the front and rear sections of the 90 top frame, utilize an arrangement illustrated in Figures 13 and 14. In this form, the boxes which house the gears are dispensed with, and the forward end of the rear frame 8 is provided with the out-turned stops 34 which limit the forward or extending movement of the front frame 4 with reference to the rear frame 8. The rear ends of the 95 side bars of the front frame 4, in this instance, are provided with the disks 31 having the notches 31', into which the ends of hooks 32 connected with 100 the upper ends of the brace members 12 engage when the top frame work is in extended position, as indicated in Figure 13. This inter-engagement of the disks and hooks retains the frame sections 4 and 8 in locked position until the braces are 105 broken. When this occurs, the movement of the brace members 12 will withdraw the hooks from the notches in the disks, allowing the forward frame member to be folded back upon the rear frame member 8 and the latter to be folded down 110 upon the back bars. The cross rod 33 connecting the hooks 32 insure the simultaneous action of the latter in locking and unlocking the frame work.

I may provide a detachable connection between 115 the forward frame of my rumble seat top, and the original top 5 of the machine, and in doing this, I may utilize the pieces 22, fastened to the rear faces of the forward cross bar 6, and extending therebelow, in conjunction with the studs 21 fastened to the original top, the lower ends of the 120 pieces 22 being slotted or recessed, as at 22' to fit over the rear reduced and threaded ends of the studs and to be locked thereagainst by the threaded knobs 39. This construction is shown 125 in Figure 9. The studs may be fastened to the original top by having their forward ends reduced and threaded and passed through openings made therein, to be secured on the inside by the lock washers and nuts, indicated at 40. The construction illustrated is one which will be found 130 suitable when the rear wall of the original top is made of metal. In case of wood or wood and c'oth construction of the back wall of the original top, other suitable connecting means between the stud 135 and back wall may be used.

I take advantage of the ability to detachably 140 connect my rumble seat top with the original top to provide a water tight joint between these parts. In order to do this, I may form the forward bar 6 of a curvature which is less than the curvature of 145 the rear wall of the original top, as illustrated in Figure 11, or when the rear wall of the original top is straight, of a curvature reversed to that of Figure 11, as shown in Figure 12, the curvature in each 150 instance being such that before attachment the

nearest point of the front bar to the original top occurs between the studs 21, as illustrated in these figures, and use a weather strip 23 extending the length of the front bar, which strip is sewed to 5 the cover material 24 where the latter extends over the forward face of the bar. In either instance, when the pieces 22 are fitted over the studs, and the knobs 39 screwed down, the front bar, in assuming the curvature of the original 10 top in the case of Figure 11, or in straightening out in the case of Figure 12, clamps the weather strip 23 against the permanent top and squeezes it tight to make a water proof connection. The central portion of the weather strip may be higher in 15 the middle of the bar and slope off towards its ends, so as to form a drain for throwing the water to both sides of the top. The weather strip may be in the nature of rubber or rubber covered material, sewed to the top covering material where 20 the latter folds over the forward face of the cross piece 6.

The top material 24 at its forward edge, where it folds over the forward and under edges of the cross bar 6, is attached to the rear face of such 25 cross bar by a suitable number of snap fasteners 41, one of which is shown in Figure 17. The lateral edges of the top material may lap over the forward and rear frame sections 4 and 8, respectively, to be connected thereto by the snap fasteners 42. The cover material extends down over 30 the back frame section, to be attached by suitable fasteners 43 to the back bars 16 thereof, and when the top is extended, the rear edge of the top material is preferably attached to the rear face 35 of the seat back 3 near the upper edge of the latter, by suitable snap fasteners 44. At the corner formed by the rear and back frame sections, the top material extends down in a triangular piece 24' to hang on the inside of the brace members 40 12-14, and the lower edge of this triangular piece preferably takes the general conformation of the brace members. The notches 45 and 46 are provided in the material to allow the triangular section to extend on the inside of the braces. When 45 the top is to be folded for storage purposes, the fastenings 44 are undone. The top material can then fold with and be stored with the frame-work. It will be understood that the fastening of the rear edge of the top material to the seat back, is 50 not a necessity, but may be practiced to make a more weather-proof connection. The lower extremities of the triangular pieces 24' may, if desired, be attached by snap fasteners 47 to the side pieces of the frame which encloses the seat back 55 upholstery 37, where such frame is utilized, as indicated in Figure 18, but this likewise is not a necessity, being done merely for the purposes of making a more snug enclosure.

In ordinary weather the top material will form 60 sufficient protection to the occupants of the rumble seat. In stormy weather, however, it is desirable to use side curtains, and these I have provided. They appear in Figures 16-19 at 25. These curtains at their upper edges are detachably connected with the side bars of the forward frame section 4 by means of hooks 30, the upper edges of the side curtains preferably extending up beyond the lower edges of the side edges of the top material. The side curtains are cut on 65 the bias at their rear upper portions to overlap the lower edges of the triangular pieces of the top cover material, and are fastened to the lower edges of the latter by suitable detachable fastening means 48. While the biased edges of the side 70 curtains are shown attached to the outside of

the corner pieces of the top material, it will be understood that they may, if desired, be fastened on the inside thereof. At their lower edges the side curtains extend into the gutters 27 of the rumble deck, as at 25', and are provided on the inside with flaps 49 connected by detachable snap fasteners 50 with the inner flanges of the gutter. At their forward edges, the side curtains are provided with flaps 26, which extend from the front edge of the forward frame member down the rear face of the original top and around onto the deck of the rumble, and terminate near the front end of the gutters 27, preferably slightly overlapping such ends, to provide a water shed along the joint between the side curtains and the original top and rumble deck, and to direct the water that may collect thereon into the gutter. Fasteners 26' are provided for the flaps 26 at the points where the original top joins the rumble deck. Additional fasteners between the original top and the flaps, and the rumble deck and the flap, may be provided if desired. The rear edge of the side curtains may lap over the ends of the rumble seat back. Windows 28 and 29 of suitable material, are provided in the side curtains, 90 and the back of the top material, respectively. 95

It will be observed that the top material in conjunction with the side curtains, comprises a complete enclosure for the rumble space, and that the weather-proof joint between the collapsible top, together with the water shed between the side curtains and the original top and rumble deck, provides an adequately weather tight construction at the junction of the rumble enclosure with the original top, that the water 105 turned by the rumble enclosure is directed into the gutters where it will escape to the rear, so that there will be no tendency for accumulated rain to find its way into the enclosure; that the structure whereby the side curtains embrace the 110 inner flanges of the gutters, forms a weather-tight joint along the lower edges of the curtains, and that the overlap of the rumble seat back by the top material and curtains forms an adequately tight joint at the rear of the enclosure. It 115 will be further observed that the construction is such that the side curtains may be applied by a person from within the rumble seat enclosure, and may be likewise detached from such position. 120

The foregoing description has been given for 125 purposes of clearness of understanding, and no undue limitations should be deduced therefrom, but the appended claims should be construed as broadly as permissible, in view of the prior art. 130

Notice is hereby given that the subject matter of the curtain structure described herein and illustrated in Figures 16 to 19 inclusive, is claimed in my co-pending application, Serial No. 574,630, filed as a division hereof. 135

Having thus described my invention what I claim as new, and desire to secure by U. S. Letters Patent is:—

1. The combination with the rumble seat of an automobile and its hinged back, of a pair of supports attached to the seat back and projecting forward of the same, a pair of curved links disposed in front of the seat back and within its lateral edges, said links being pivoted at their lower ends to said supports and being of such length 140 that, when raised, their outer ends will be positioned above the upper edge of the seat back, and a collapsible frame supported by said links and including top supporting members hinged together 145 and back bars and braces pivoted at their upper 150 ends to the frame.

- ends to said hinged members and at their lower ends pivoted along a common axis to the outer ends of said links, said top supporting members, back bars and braces adapted to be collapsed into a compact folded condition and to be bodily swung about the outer ends of said links to a position behind the back or to be lowered bodily with said links to a storage position between the seat and back. 80
- 10 2. In a folding top for rumble seats, the combination with the seat and its back, of a pair of supports forward of the seat back and within the lateral edges thereof, a collapsible frame including top supporting members hinged together and braces and bars pivotally connected at their upper ends with the supporting members, a pair of links to the upper ends of which the lower ends of said braces and bars are pivoted, said links at their lower ends being pivoted to said supports at points forward of said back, said links being of such length that, when raised, their upper ends will be positioned above the upper edge of the seat back, said frame adapted to be collapsed and to be bodily swung about the links to a position behind the back or to be bodily lowered by said links to a storage position between the seat and back. 90
3. In a folding top for rumble seats, the combination with the seat and its hinged back, of a collapsible top frame, including top supporting members hingedly connected together and adapted to be collapsed in overlapping position into compact form, means for supporting the top frame upon the seat back and for bodily raising and lowering the top frame as a whole with respect to the seat back, comprising a pair of links arranged forward of the seat back within the lateral edges thereof, supporting pivots at the upper ends of said links upon which the top frame is pivoted for bodily movement, supports carried by the seat back to which the links are pivoted at their lower ends, the links being of such length as, when raised, to position said supporting pivots above the seat back. 100
4. A folding top for rumble seats, comprising top supporting frame members hinged together upon which the top material is supported, a pair of supports secured to the rumble seat back, links connected at their lower ends to said supports, and hinged braces and back bars having their lower ends connected together and to the upper end of the links, and having their upper ends connected to said top supporting frame members. 110
5. In a folding top for an automobile rumble seat, the combination with the seat and its back, of a top supporting structure comprising hingedly connected top supporting members, braces and bars adapted to be collapsed in overlapping position into compact form and when so collapsed to be positioned either behind the back, or in front of the same between the back and seat, supports on the seat back projecting forwardly therefrom and curved links hinged both to the supports and to the top supporting structure, such links being longer than the distance from said supports to the upper edge of the seat back. 120
6. In a folding top for rumble seats, the combination of a supporting frame for the top material including supporting members hinged together, back bars hinged thereto, said frame members and back bars adapted to be collapsed in overlapping position, hinged braces connecting the supporting frame members with the back bars, and links to which the back bars and hinged braces are pivotally connected and hingedly connecting the top supporting frame as a whole to the seat back. 130
7. In a folding top for rumble seats, the combination of a collapsible top supporting frame comprising members hinged together upon which the top material is adapted to be supported, back bars and braces pivotally connected at their upper ends to said hinged top supporting members and pivotally connected with respect to each other at their lower ends, said frame members, back bars and braces adapted to be collapsed in overlapping position into compact form, supports adapted to be attached to the seat back, and means for connecting said back bars and braces to said supports. 140
8. A folding top for rumble seats, consisting of a flexible top, a folding frame carrying said top and composed of a pair of brackets to secure the frame to the back, a pair of links having their lower ends connected to said brackets, a pair of hinged brace members and a pair of back bars having their lower ends connected together and to the upper ends of said links, a frame connected with the upper ends of the back bars and braces, and a pair of front bars, having their inner ends connected with said frame, gear wheels on the inner ends of said bars, racks on the upper ends of said braces to mesh with said gear wheels to cause the movement of said racks to close the bars upward and backward upon said frame. 150
9. The combination of the forward seat top of an automobile, a rumble seat top adapted to be detachably connected to the back of the forward seat top and including a flexible cross member of contour differing from that of the back of the forward seat top, a weather strip carried by said cross member disposed between the same and the forward seat top, and means for clamping the cross member against the back of the forward seat top, and to distort the cross member into contour conforming to that of the seat top to thereby squeeze the weather strip between said cross member and forward seat top. 160
10. The combination with an automobile having a forward seat top, of a rumble seat top having a forward cross bar, a compressible weather strip carried by the cross bar between the same and the forward seat top, and means between the cross bar and the forward seat for drawing the cross bar toward the forward seat top to thereby squeeze the weather strip between the cross bar and the forward seat top. 170
11. In a folding top for rumble seats, the combination of a collapsible frame-work including sections pivoted together, and collapsible braces adapted to support the sections in extended position, one of the sections being provided with recessed locking members, and the braces being provided with hook members adapted to engage the recessed locking members when the frame sections are in extended position for locking the frame members in such position and adapted to release the locking members when the braces are collapsed, for allowing the frame sections to collapse with respect to each other. 180
12. In a folding top for rumble seats, the combination of frame members pivoted together and adapted to be extended and collapsed with reference to each other, collapsible braces for supporting the frame members in extended position, and locking members movable with the brace members, co-operating locking means carried by one of the frame members, the locking means on the brace members adapted to be 190

brought into engagement with the said locking means on the frame member when the frame members and the braces are in extended position, to thereby lock the frame members in such 5 extended position, the locking members on the braces adapted to be disengaged from the locking means on the frame member when the braces are collapsed to thereby allow the frame members to be collapsed with respect to each other.

10 13. In combination, an automobile body hav-

ing a top and a rumble seat, a frame having side bars, and a cross bar secured to and carried by the side bars for engaging the rear side wall of the top, arms secured to the back of the rumble seat and to the rear ends of the side bars, 80 a cover for the frame having its front end secured to the cross bar, and a gasket carried by the cross bar contacting with the rear side wall of the top.
